SURFACING MACHINE

John P. Bruck, Toledo, Ohio, assignor to American Lincoln Corporation, Toledo, Ohio, a corporation of Ohio

Application November 19, 1958, Serial No. 775,010

6 Claims. (Cl. 51—170)

This invention is an improvement over the invention disclosed in my co-pending application Serial No. 703,970, filed December 19, 1957.

The invention sought to be covered in this application is an improvement for adjusting the yoke block in relation to the channel plate. The feature of adjusting the channel plate in relation to the pad supporting plate is claimed in said co-pending application.

This invention relates to surfacing machines, and particularly to those of the power driven hand operated type, and its primary object is the provision in such a machine of improved means for translating a rotary movement of a part of the power means into a reciprocating movement of the surfacing pad.

A further object of the invention is the provision of means for causing said movement translating means to impart an orbital instead of a reciprocating movement to the pad.

Further objects and advantages of the invention will be apparent from the following detailed description, and from the accompanying drawings illustrating one embodiment thereof, and in which—

Fig. 1 is a central vertical section of the machine, with parts in full;

Fig. 2 is a section on the line 2—2 in Fig. 1, with the pad driving connection set for translatory movement of the pad;

Fig. 3 is an enlarged top plan view of a pad supporting plate with the adjustable plate moving means involving the subject matter of the present invention also shown in top plan view;

Fig. 4 is a side elevational view of the pad supporting plate or platen;

Fig. 5 is a top plan view of a selectively movable yoke involved in the invention;

Fig. 6 is a central vertical sectional view of the yoke as observed in the plane of line 6—6 on Fig. 5;

Fig. 7 is a fragmental view for the most part in vertical section as observed in the planes of the broken line 7—7 on Fig. 3;

Fig. 8 is a view similar to Fig. 7 wherein cooperating elements have been adjusted for orbital movement of the pad supporting plate;

Fig. 9 is an end elevational view of an adjusting cam involved in the invention; and

Fig. 10 is a side elevational view of said cam.

Referring to the drawings, 1 designates the body casting or frame of the machine which, in the present instance, is of inverted pan-shape and has on its front end portion a motor housing 2 for an electric operating motor 3. This housing has a handle 4 projecting rearwardly therefrom over its rear end, and the customary motor lead wires extend therethrough. The motor control switch trigger 5 is located at the inner end of the handle, as is customary in machines of this type.

The body casing 1 is supported above and united to a surfacing pad supporting platen 6 by a plurality of

2

posts 7 of rubber or other suitable material, preferably of a resilient nature. The pad 6 is preferably of flat, stiff sheet-like material faced at its under side with a pad-like part 8 and over this is drawn a strip of sandpaper 9 or other suitable surfacing material. The ends of this material, in the present instance, are doubled over the respective ends of the plate 6 and clamped thereto by a bar 10 which, in turn, is held by a clamping finger 11 secured to elongated bosses 12 unitary with plate 6.

Mounted on top of the plate 6 substantially centrally thereof is an upwardly facing channel plate 13 which is fixed to the plate 6 and which embodies a rectangular bottom wall 14 and opposite parallel side walls 15 and 16.

15 A yoke block 17 of rectangular form in plan is disposed within the channel plate 13 and same includes an upwardly projecting bearing receiving cylindrical portion 18 and the block is provided at one edge thereof with a vertical slot 19 for a purpose later to appear.

20 The motor shaft 20 extends down into the body casing 1 through its top wall and has suitable driving connection with a member 21 mounted for rotary movement on a vertical stub shaft 22 fixedly projecting down into the 25 body casing from its top and substantially at its center.

The member 21 is provided at its lower end with a 30 stub shaft 23 which is eccentric to the axis of rotation of member 21 and operatively connects with the yoke 35 17 through a bearing 24 therein whereby orbital movement of the stub shaft 23 normally imparts reciprocating movements to the yoke block 17 in the guide channel 13.

35 At this point it is to be observed that for reciprocating movement of the plate 6 longitudinally thereof, the central longitudinal axis of the guide channel is preferably disposed at approximately 10° angular relation to the longitudinal center line of the plate due to the 40 mass of the medianism and the frictional resistance between the channel plate 13 and the yoke block 17.

The aforementioned reciprocating movement of the yoke block imparts reciprocating movement to the plate 6 substantially longitudinally thereof due to the component action of the orbital movement of the yoke block 45 on the flanges 15 and 16 of the channel member.

The primary feature of the present invention is the provision of adjustable means operative to lock the yoke block against reciprocating movement in the channel plate and to permit such movement at will whereby in the first instance the orbital movement of shaft 23 will be directly transferred to the plate 6.

The means above referred to are particularly illustrated in Figs. 3 and 7 to 10 inclusive, wherein it will be seen that a vertical slot 25 is provided in the side wall 16 of the channel plate 13 and which slot extends a substantial distance into the bottom wall 14. Also, the yoke block 17 is provided with a vertical slot 19 in alignment with the slot 25.

60 A cam member is disposed adjacent the channel plate 13 and same comprises a shaft 27 having a polygonal head 28 on one end thereof and a cam 29 on the opposite end thereof.

The head 28 is provided with a polygonal key receiving opening 30 which is accessible through an aperture 31 in one of the side walls 6a of the plate 6 and the cam 29 is substantially a quadrant of a circle in side view and includes opposed right angular edges 31 and 32, the latter of which is the vertex of oppositely inclined wall portions 33. The cam member is held in operative position by means of a spring 34 including a

tongue 35 which is secured to plate 6 and an arcuate portion 36 yieldably engaged with the shaft 27 for holding the cam in either of the two alternate positions shown in Figs. 7 and 8.

With the cam in the position in Fig. 7, the yoke block 17 is free to slide in the channel plate 13 with a resulting reciprocatory or fore and aft movement of the plate 6, whereas when the cam is moved to the position in Fig. 8, the yoke block 17 is locked against reciprocatory movement in the channel plate 13 and orbital movement of the plate 6 results.

By the provision of the tapered edge 32 on the cam, the cam may be readily moved from the position in Fig. 7 to that in Fig. 8 should the slots 25 and 26 be mis-aligned in the relative movement of the channel plate and the yoke block.

From the above description, it will be apparent that a surfacing machine is provided, which is capable of being expeditiously adjusted by relatively simple means for effecting reciprocatory or orbital movement of the pad.

It is to be understood that the present invention is not limited to any specific construction, arrangement or form of the cooperating parts, since it is capable of numerous modifications and changes without departing from the spirit of the claims.

I claim:

1. In a surfacing machine having a body, a pad supporting the body by means of a plurality of resilient posts for relative vibrating movement, a power mechanism carried by the body and having an orbital movement member driven by the power mechanism adjacent the pad, the pad having a channel plate rigidly mounted on the top thereof, a yoke member supported by said channel plate for slidable movement therein, said yoke member receiving said orbital movement member for vibratory movement of said pad; and means supported by said pad externally of said channel plate for locking said yoke member

against movement in said channel plate for orbital movement of the pad.

2. A surfacing machine according to claim 1, wherein said means comprises alignable vertical slots in adjacent sides of said channel plate and said yoke member, and a cam member rotatably supported by said pad for movement into and out of said slots for locking said yoke member against movement in said channel member when in the first named position.

3. A surfacing machine according to claim 2, wherein said cam is supported on one end of a shaft; means rotatably supporting said shaft on said pad and adjacent said channel plate and key operable means on the other end of said shaft.

4. A surfacing machine according to claim 3, wherein said pad comprises a plate on which said channel plate is supported, said first plate having opposite side flanges adjacent one of which said key operable means is disposed, and said one of said flanges being provided with an aperture adjacent said key operable means for reception of a key for engagement with said key operable means.

5. A surfacing machine according to claim 3, wherein said rotatably supporting means comprises a leaf spring including a shank portion secured to said pad and an arcuate portion yieldingly bearing on said shaft.

6. A surfacing machine according to claim 2, wherein said cam member is quadrant shaped and having a radial tapered edge for admission into said slots whether or not same are in alignment.
